Fig. 10

Fig. 12

FIGURE 1 is a top plan of the Rook, or Castle of a set of chessmen showing my new design.

FIGURE 2 is a side elevation of the Rook, or Castle.

FIGURE 3 is a top plan of the Knight.

FIGURE 4 is a side elevation of the Knight.

FIGURE 5 is a top plan of the Bishop.

FIGURE 6 is a side elevation of the Bishop.

FIGURE 7 is a top plan of the Queen.

FIGURE 8 is a side elevation of the Queen.

FIGURE 9 is a top plan of the King.

FIGURE 10 is a side elevation of the King.

FIGURE 11 is a top plan of the Pawn.

FIGURE 12 is a side elevation of the Pawn.

FIGURES 2, 4, 6, 8, 10 and 12 show the side elevation of the respective pieces regardless of the direction from which they are viewed.

I claim:

The ornamental design for a set of chess men, as shown and described.
